BAYONET SCABBARD

Edwin L. Beckwith, Harvard, Mass., assignor to Beckwith-Arden Inc., Watertown, Mass., a corporation of New Hampshire

Filed Oct. 27, 1964, Ser. No. 82,337

Term of patent 14 years

(Cl. D22—6)

FIG. 1 is a view in front elevation of a bayonet scabbard showing my new design,

FIG. 2 is a view in side elevation,

FIG. 3 is a view in rear elevation,

FIG. 4 is a top plan view, and

FIG. 5 is a sectional view on the line 5—5 of FIG. 1.

I claim:

The ornamental design for a bayonet scabbard, substantially as shown.
